UNITED STATES PATENT OFFICE.

NEWMAN H. HOLLAND, OF WEST ORANGE, NEW JERSEY, ASSIGNOR TO NEW JERSEY PATENT COMPANY, OF WEST ORANGE, NEW JERSEY, A CORPORATION OF NEW JERSEY.

PHONOGRAPH.

1,272,262.

Specification of Letters Patent. Patented July 9, 1918.

Application filed November 27, 1916. Serial No. 133,671.

To all whom it may concern:

Be it known that I, NEWMAN H. HOLLAND, a subject of the King of Great Britain, and a resident of West Orange, Essex county, 5 New Jersey, have invented certain new and useful Improvements in Phonographs, of which the following is a description.

My invention relates to phonographs and more particularly to an improved device by 10 which instructions may be readily noted for any desired part of the phonograph record.

In my United States Patent No. 1,106,448, granted August 11, 1914, I show a phonographic memorandum device in which a 15 straight edge extends across the face of a holder for a memorandum sheet, the straight edge and the holder being movable relatively to each other at a speed corresponding with that of the phonograph recorder or reproducer across the record surface. A pencil is 20 arranged to be drawn along the straight edge to mark the memorandum sheet to note the position on the phonograph record of any particular recorded matter to which attention is to be directed. In my present 25 invention, I eliminate the use of a separate memorandum sheet and the holder therefor, the instructions and the parts of the record to which they apply being indicated by 30 marks made upon the record tablet itself.

The principal object of my invention is to provide an improved device of the character referred to. Other objects of my invention will appear more fully in the following specification and appended claims.

In order that my invention may be more clearly understood, attention is hereby directed to the drawing forming a part of this specification, and in which:—

40 Figure 1 represents a side elevation of a phonograph embodying one form of my invention;

Fig. 2 represents a front elevation thereof, 45 parts of the phonograph being broken away; and

Fig. 3 represents a plan view of a detail of the same.

In all the views, like parts are designated by the same reference characters.

50 The phonograph shown is of the Edison type and comprises the usual body A having a back rod 1 and a guide rod 2 on which the traveling carriage 3 is slidably mounted so as to permit the sound box 4, which is supported in the forward end of the carriage,

to travel across the cylindrical tablet 5 carried by the rotatable support 6. The latter may be a collapsible mandrel constructed as shown in my United States Patent No. 1,167,500. The sound box herein shown is 60 provided with a recording stylus 7 whereby the undulations corresponding to the sounds to be recorded are cut into the surface of the tablet 5. The support 6 may be rotated by a motor (not shown), as is common in 65 the art. The sound box carriage may be fed along the record by feeding means comprising a rotatable feed screw 8 engaged by a feed nut 9 supported at the end of a spring 10 carried by the traveling carriage. An 70 arm 11 projecting forwardly from the traveling carriage below the spring 10 carries a screw 12 bearing on the under side of the spring 10 to regulate the pressure of the feed nut 9 on the feed screw 8. The latter 75 may be rotated from the phonograph mechanism by means well known in the art. The carriage 3 is pivotally mounted on the back rod 1 so as to permit elevation thereof for the purpose of disengaging the stylus 7 from 80 the surface of the record tablet 5 and at the same time to disengage the feed nut 9 from the feed screw 8. The device thus far specifically described is well known in the art, and *per se* forms no part of the present invention. 85

At the forward end of the arm 11 on opposite sides thereof, levers 13 and 14 are pivotally supported as by means of pivot screws 15 and 16 threaded into the said arm. 90 Each of these levers is provided with a substantially horizontal portion 17 extending under the record tablet 5 to the forward part of the machine and also with an upwardly extending portion 18 terminating in proximity to the record tablet. Springs 19 and 20 connected to the upwardly extending arms of the levers 13 and 14 respectively tend to hold the upper ends of said arms away from the record tablet and in engagement with 95 stops, one of which is shown at 21. The forward ends of the arms 17 are provided with buttons or finger pieces 22 and 23 respectively, whereby the levers 13 and 14 may be rotated against the action of the springs 19 and 20. Rotatably mounted on the upper end of each of the upwardly extending arms 18 of the said levers is a disk 24 of yielding material such as felt, rubber or the like. Because of the yielding char- 105 110

acter of this material there is no danger of damaging the surface of the record tablet by the removal or displacement of record material or otherwise, or of damaging or 5 obliterating the sound record impressions when the marker is brought into engagement with the tablet. These disks 24 may be secured to the levers by means of screws 25 and they may be held in suitable spaced 10 relation with respect to the levers by means of washers 26, one of which is placed between each disk and the corresponding lever. The upper end of each of the levers is provided with a rearwardly extending 15 portion 27 formed with a claw like part 28 constituting a holder in which a pad 29 may be suitably held by friction or otherwise. The pads 29, one which may be the well known inking pads serve as means for 20 holding a suitable coloring matter. The marking ink or other marking fluid should be of different color from that of the tablet 5 so as to be readily discernible thereon. The rotatable disks are constantly in engagement with the pads, and when either 25 of the levers is depressed to bring its disk in engagement with the record tablet, the tablet by its rotation causes the disk to be rotated and its periphery to be supplied 30 with ink or other suitable marking fluid from the pad, whereupon the periphery of the disk causes a ring of the color of the marking fluid to be made around the tablet. Each of the rotatable disks is made compara- 35 tively thin so that a comparatively narrow line is made thereby upon the record tablet. The disks as shown are in alinement with each other and are in the same plane at right angles to the axis of rotation of the 40 tablet support as the stylus 7; so that a mark made upon the tablet by either disk will indicate the exact position of the stylus along the tablet at the time the mark was made thereon. The pads may be supplied 45 with ink or marking fluid of different colors to indicate different kinds of instructions, for example, the length of the letter, or that a correction is to be made in the letter at the place marked. The correction may be 50 dictated upon the cylinder at the marked place. Fig. 3 shows in plan buttons or finger pieces 22 and 23 bearing the inscriptions "Length," "Correction," indicating that the button 23 is to be depressed to bring 55 the marking device into operation for designating the beginning or the end of a letter, and that the button 22 is to be depressed to indicate the place where a correction is to be made in the letter.

60 In transcribing, the operator, because of the marks on the cylinder 5, has her attention called in advance to the lengths of the letters and to the places where corrections are to be made.

65 While I have shown only two markers,

any desired number may be used for indicating different instructions. Various means other than those described may also be used for placing the desired marks upon the record tablet. In short, my invention is not 70 limited to the specific disclosure, but includes all the modifications coming within the scope of the appended claims.

Having now described my invention, what I claim as new and desire to protect by Let- 75 ters Patent is as follows:—

1. The combination of a rotatable support for a record tablet, a stylus in operative relation thereto, said support and stylus being movable with respect to each other, and 80 means for marking the surface of a tablet carried by said support without damaging the same, said marking means being mounted to automatically occupy different positions with respect to the tablet for different 85 positions of said stylus with respect to the tablet, substantially as described.

2. The combination of a rotatable support for a record tablet, a stylus in operative relation thereto, said support and stylus being movable with respect to each other, and 90 yielding means for marking the surface of a tablet carried by said support, said marking means being mounted to automatically occupy different positions with respect to the tablet, substantially as 95 described.

3. The combination with a rotatable support for a record tablet, of rotatable means 100 mounted in proximity thereto for marking the surface of a tablet carried by said support, substantially as described.

4. The combination of a rotatable support for a record tablet, a stylus in operative relation thereto, said support and stylus being movable with respect to each other, and 105 rotatable means for marking the surface of a tablet carried by said support, said marking means automatically occupying different positions with respect to the tablet for different positions of said stylus with respect to said support, substantially as described.

5. The combination of a rotatable support for a record tablet, a stylus in operative relation thereto, said support and stylus being movable with respect to each other, and 110 means for marking the surface of a tablet carried by said support with a mark of different color from that of the tablet, said marking means being mounted to automatically occupy different positions with respect to the surface of the tablet for different positions of said stylus with respect to the 115 surface of the tablet, substantially as described.

6. The combination with a support for a record tablet, of means mounted in proximity to said support for marking the sur- 120 125 130

face of the tablet with a mark of different color from that of the tablet, substantially as described.

7. The combination of a rotatable support for a record tablet, a stylus in operative relation thereto, said support and stylus being movable with respect to each other, means for marking the surface of the tablet with a mark of different color from that of the tablet, and means for automatically supplying coloring matter to said marking means, said marking means being mounted to automatically occupy different positions with respect to the surface of the tablet for different positions of said stylus with respect to the surface of the tablet, substantially as described.

8. The combination with a support for a record tablet, means mounted in proximity to said support for applying coloring matter to the surface of the tablet to mark the same, and means for supplying coloring matter to said marking means, substantially as described.

9. The combination with a support for a record tablet, means mounted in proximity to said support for applying coloring matter to the surface of the tablet to mark the same, and means comprising a pad for automatically supplying coloring matter to said marking means, substantially as described.

10. The combination with a support for a record tablet, of means for marking the surface of the tablet without damaging the same and means for moving said marking means into engagement with the surface of the tablet, substantially as described.

11. The combination with a support for a record tablet, of means for marking the surface of the tablet without damaging the same, means for moving said marking means into engagement with the surface of the tablet, and means for automatically moving said marking means away from the surface of the tablet, substantially as described.

12. The combination with a support for a record tablet, of means mounted in proximity to said support for at will providing the surface of the tablet with different kinds of marks to indicate different memoranda without damaging the surface of the tablet, substantially as described.

13. The combination with a support for a record tablet, of yielding means mounted in proximity to said support for providing the surface of the tablet with different kinds of marks to indicate different kinds of memoranda, substantially as described.

14. The combination of a support for a record tablet, a stylus in operative relation thereto, said support and stylus being mov-

able with respect to each other and means for providing the surface of the tablet with different kinds of marks to indicate different memoranda, said marking means being mounted to automatically occupy different positions with respect to the tablet for different positions of said stylus with respect to the tablet, substantially as described.

15. The combination of a rotatable support for a record tablet, a stylus in operative relation thereto, said support and stylus being movable with respect to each other, and means for marking the surface of a tablet carried by said support without damaging the same, said marking means being mounted to occupy different positions with respect to the tablet for different positions of said stylus with respect to the tablet, substantially as described.

16. The combination of a rotatable support for a record tablet, a stylus in operative relation thereto, said support and stylus being movable with respect to each other, and yielding means for marking the surface of a tablet carried by said support, said marking means being mounted to occupy different positions with respect to the tablet for different positions of said stylus with respect to the tablet, substantially as described.

17. The combination of a rotatable support for a record tablet, a stylus in operative relation thereto, said support and stylus being movable with respect to each other and means for depositing marking material on the surface of the tablet carried by said support, said marking means being mounted to occupy different positions with respect to the surface of the tablet for different positions of said stylus with respect to the surface of the tablet, substantially as described.

18. The combination of a rotatable support for a record tablet, a stylus in operative relation thereto, said support and stylus being movable with respect to each other, a plurality of means for depositing upon the surface of the tablet marking material, lying substantially in the same plane with each other and with said stylus, and movable to occupy different positions with respect to the surface of the tablet for different positions of said stylus with respect to the surface of the tablet and means for actuating said marking means, substantially as described.

This specification signed and witnessed this 21st day of November, 1916.
